TYPEWRITING MACHINE

Henry J. Hart, West Hartford, Conn., assignor
to Royal Typewriter Company, Inc., New York,
N. Y., a corporation of New York

Application October 21, 1935, Serial No. 46,015

13 Claims. (Cl. 197—88)

This invention relates to new and useful improvements in typewriting machines generally, although more particularly to the carriage escapement mechanism thereof.

It is the common practice to provide an escapement which is fully released for a step movement during the return movement of the spacing bar. Thus, it is necessary for the operator to wait until after the spacing bar has been fully depressed and returned to normal position before actuating a key lever.

The principal object of my invention is to provide a carriage escapement mechanism which is fully releasable during the operating stroke of an operating lever, such as for instance, the spacing bar lever, thereby permitting the operation of a key lever prior to the spacing bar beginning its return movement.

In the drawings:

20 Figure 1 is a vertical sectional view, partly in elevation, embodying my invention.

Figure 2 is an enlarged front elevation of the escapement mechanism.

25 Figure 3 is a horizontal sectional view taken on the line 3—3 of Figure 2.

Figure 4 is an enlarged vertical section taken on the line 4—4 of Figure 3.

Figure 5 is a perspective view of the interponent, and

30 Figures 6, 7 and 8 are enlarged detail plan views showing different positions of the interponent during depression of the spacing bar.

Referring to the accompanying drawings, 5 designates an escapement supporting frame of a typewriting machine having a carriage 6 supported thereon in the usual manner. The usual escapement mechanism for the carriage includes a rack 7 which is mounted on the carriage for cooperation with a pinion 8 loosely mounted on a shaft 9 journaled in the frame 5, and fixed to said shaft is the usual escapement wheel 10 having a back dog 11 pivoted thereon and yieldably engaging the teeth of the pinion 8. A dog rocker 12 is fulcrumed on pivots 13, 13 to swing about a horizontal axis, and mounted on the rocker above the axis thereof are pivoted and fixed dogs 14 and 15 respectively which are successively engaged by the teeth of the escapement wheel 10 when the rocker is rocked to feed the carriage step-by-step in letter space intervals. The rocker 12 is normally held against rearward swinging movement by a spring 16 whereby the pivoted or limber dog 14 is normally held in engagement with the escapement wheel 10, the fixed

dog 15 being normally disposed in front of said wheel.

A spacing bar 17 is mounted on the front ends of levers 18 (one only being shown) which are fulcrumed as at 19 on a bridge 20 rigidly connected to the side walls of the main frame of the machine, one of said levers terminating in an upwardly extending rock arm 21. In the broad sense, the two levers 18 and the spacing bar 17 constitute a manually depressible lever. 5 A rearwardly extending spring 22 which is connected at one end to the arm 21 and at the other end to a stud 23 fixed to the machine frame, serves to yieldably retain the spacing bar 17 and levers 18 against a stop 18a and against 15 depression.

A bracket 24 is attached to the frame 5 at one side of the rocker 12, and a power transmitting lever 25 which extends in a general direction away from the rocker and in a plane parallel to the axis 19, is fulcrumed intermediate its ends on said bracket, as at 26, 26, to swing about a vertical axis. The power end 27 of the lever 25 is connected to the rock arm 21 by a link 28. The other end 29 of the lever 25 is disposed in a plane slightly in front of the rocker 12, and an interponent 30 is fulcrumed intermediate its ends as at 31 on said end 29 of the lever and has bodily movement with the latter. The interponent includes a tail 32 at one end and a nose 33 having a concentric edge 34 at the other end. A coil spring 35 is connected at one end to the end 29 of the lever 25 and at its other end to the tail 32 of the interponent, and serves the dual function of (1) yieldably retaining the tail 32 against a stop 36 on the end 29 of the lever 25 and (2) yieldably retaining the concentric edge 34 of the nose 33 of the interponent in engagement with the front face of a laterally extending bearing arm 37 fixed to the upper portion of the rocker 12. A fixed abutment 38 which is preferably an integral part of the bracket 24, is located in spaced relation to and in rear of a laterally extending cam arm 39 fixed to the interponent. It will be observed that the pivot 31 of the interponent is directly in front of the bearing arm 37 of the rocker and that normally the major axis of the interponent lies in a plane at substantially right angles to the general plane of the rocker 12. 40 45 50

It will be observed that in Figure 6 the interponent 30 and the dog rocker 12 are in their normal or rest positions; that in Figure 7 the transmitting lever 25 has been moved to shift the interponent rearwardly and to swing the 55

upper portion of the dog rocker rearwardly to permit the fixed dog 15 to be engaged by the next tooth of the escapement wheel 10, that the interponent has been swung into a position 5 whereby it is about to become disengaged from the dog rocker, and that this movement of the interponent is effected during the first portion of the depression movement of the spacing bar, or in other words, during the operating stroke 10 of the operating lever; and that in Figure 8 the lever 25 has been moved to its limit by reason of the spacing bar reaching the end of its depression movement, the interponent has been released from the dog rocker, and the latter has 15 returned to its normal position with the limber dog 14 in engagement with the tooth of the escapement wheel.

From the foregoing, it will be understood that a complete step movement is imparted to the 20 carriage during the depression of the spacing bar and prior to said bar reaching the end of said depression movement.

I claim:

1. In a typewriting or like machine, an escapement mechanism including an escapement wheel, a dog rocker, fixed and movable dogs mounted on said rocker for alternately engaging the escapement wheel, and a spring for normally holding the rocker against movement; an operating lever; and means operated by said lever for rocking the dog rocker against the tension of the spring and for releasing said rocker during the operating stroke of said lever, said means including a bodily movable and pivotally mounted interponent normally and directly engaging said rocker and movable to disengage said rocker, a spring for normally retaining the interponent in engagement with the rocker, and means disposed in the path of movement of the interponent for swinging the latter out of engagement with the rocker.

2. In a typewriting or like machine, an escapement mechanism including an escapement wheel, a dog rocker, fixed and movable dogs mounted on said rocker for alternately engaging the escapement wheel, and a spring for normally holding the rocker against movement; an operating lever; and means operated by said lever for rocking the dog rocker against the tension of the spring and for releasing said rocker during the operating stroke of said lever, said means including a bodily movable and pivotally mounted interponent normally and directly engaging said rocker and movable to disengage said rocker and provided with a cam arm, a spring for normally retaining the interponent in engagement with the rocker, and a fixed abutment mounted for cooperation with the cam arm of the interponent for swinging the latter out of engagement with the rocker during the bodily movements of the interponent.

3. In a typewriting or like machine, an escapement mechanism including a dog rocker swingable about a horizontal axis, and a spring for normally holding the rocker against movement; an operating lever; and means operated by said lever for rocking the dog rocker against the tension of the spring and for releasing said 65 rocker during the operating stroke of said lever, said means including a power transmitting lever mounted to swing about a vertical axis, and an interponent pivotally mounted on and bodily movable with said transmitting lever and normally engageable with said rocker, said inter-

ponent being swingable to disengage said rocker upon movement of said transmitting lever.

4. In a typewriting or like machine, an escapement mechanism including a dog rocker swingable about a horizontal axis, and a spring for normally holding the rocker against movement; an operating lever; and means operated by said lever for rocking the dog rocker against the tension of the spring and for releasing said rocker during the operating stroke of said lever, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, a spring for normally retaining the interponent in engagement with the rocker, and means disposed in the path of movement of the interponent for swinging the latter out of engagement with the rocker.

5. In a typewriting or like machine, an escapement mechanism including a dog rocker swingable about a horizontal axis, and a spring for normally holding the rocker against movement; an operating lever; and means operated by said lever for rocking the dog rocker against the tension of the spring and for releasing said rocker during the operating stroke of said lever, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, said interponent being provided with a cam arm, a spring for normally retaining the interponent in engagement with the rocker, and a fixed abutment mounted for cooperation with the cam arm of the interponent for swinging the latter out of engagement with the rocker during the bodily movements of the interponent.

6. In a typewriting or like machine, an escapement mechanism including a supporting frame, a dog rocker pivoted on said frame to swing about a horizontal axis, and a spring for normally holding the rocker against swinging movement; an operating lever; and means operated by said lever for rocking the dog rocker against the tension of the spring and for releasing said rocker during the operating stroke of said lever, said means including a power transmitting lever fulcrumed on the frame to swing about a vertical axis, operating connections between said levers, an interponent mounted on and bodily movable with the transmitting lever to swing about a vertical axis and normally engaging the dog rocker, said interponent being provided with a cam arm, a spring for normally retaining the interponent in engagement with the rocker, and a fixed abutment mounted on the frame and for cooperation with the cam arm of the interponent for swinging the latter out of engagement with the rocker during the bodily movements of the interponent.

7. In a typewriting or like machine, an escapement mechanism including an escapement wheel, a dog rocker, fixed and movable dogs mounted on said rocker for alternately engaging the escapement wheel, and a spring for normally holding the rocker against movement; a depressible spacing bar; and means operated by said bar for rocking the dog rocker against the ten-

sion of the spring and for releasing said rocker during the depressing movement of said bar, said means including a bodily movable and pivotally mounted interponent normally engaging said rocker and movable to disengage said rocker, a spring for normally retaining the interponent in engagement with the rocker, and means disposed in the path of movement of the interponent for swinging the latter out of engagement with the rocker.

8. In a typewriting or like machine, an escapement mechanism including an escapement wheel, a dog rocker, fixed and movable dogs mounted on said rocker for alternately engaging the escapement wheel, and a spring for normally holding the rocker against movement; a depressible spacing bar; and means operated by said bar for rocking the dog rocker against the tension of the spring and for releasing said rocker during the depressing movement of said bar, said means including a bodily movable and pivotally mounted interponent normally engaging said rocker and movable to disengage said rocker and provided with a cam arm, a spring for normally retaining the interponent in engagement with the rocker, and a fixed abutment mounted for cooperation with the cam arm of the interponent for swinging the latter out of engagement with the rocker during the bodily movements of the interponent.

9. In a typewriting or like machine, an escapement mechanism including a dog rocker swingable about a horizontal axis, and a spring for normally holding the rocker against movement; a depressible spacing bar; and means operated by said bar for rocking the dog rocker against the tension of the spring and for releasing said rocker during the depressing movement of said bar, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever.

10. In a typewriting or like machine, an escapement mechanism including a dog rocker swingable about a horizontal axis, and a spring for normally holding the rocker against movement; a depressible spacing bar; and means operated by said bar for rocking the dog rocker against the tension of the spring and for releasing said rocker during the depressing movement of said bar; said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, a spring for normally retaining the interponent in engagement with the rocker, and means disposed in the path of movement of the interponent for swinging the latter out of engagement with the rocker.

11. In a typewriting or like machine, an escapement mechanism including a dog rocker swingable about a horizontal axis, and a spring for normally holding the rocker against movement; a depressible spacing bar; and means operated by said bar for rocking the dog rocker against the tension of the spring and for releasing said rocker during the depressing movement of said bar, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, said interponent being provided with a cam arm, a spring for normally retaining the interponent in engagement with the rocker, and a fixed abutment mounted for cooperation with the cam arm of the interponent for swinging the latter out of engagement with the rocker during the bodily movements of the interponent.

12. In a typewriting or like machine, an escapement mechanism including a supporting frame, a dog rocker pivoted on said frame to swing about a horizontal axis, and a spring for normally holding the rocker against swinging movement; a depressible spacing bar; and means operated by said bar for rocking the dog rocker against the tension of the spring and for releasing said rocker during the depressing movement of said bar, said means including a power transmitting lever fulcrumed on the frame to swing about a vertical axis, operating connections between said bar and lever, an interponent mounted on and bodily movable with the transmitting lever to swing about a vertical axis and normally engaging the dog rocker, said interponent being provided with a cam arm, a spring for normally retaining the interponent in engagement with the rocker, and a fixed abutment mounted on the frame and for cooperation with the cam arm of the interponent for swinging the latter out of engagement with the rocker during the bodily movements of the interponent.

13. In a typewriting or like machine, an escapement mechanism including a dog rocker, and a spring for normally holding the rocker against movement; a depressible spacing bar and a lever supporting said bar; and means operated by said bar for rocking the dog rocker against the tension of the spring and for releasing said rocker during the depression movement of the bar, said means including a transmitting lever, a link connecting the spacing bar lever and the transmitting lever, and an interponent pivotally mounted on and bodily movable with said transmitting lever and normally engageable with said rocker, said interponent being swingable to disengage said rocker upon movement of said transmitting lever.

HENRY J. HART.
